UNITED STATES PATENT OFFICE.

HARRIS T. DUNBAR, OF BUFFALO, NEW YORK.

SELF-BAILING SCOW.

1,424,452.

Specification of Letters Patent. Patented Aug. 1, 1922.

Application filed May 14, 1921. Serial No. 469,431.

To all whom it may concern:

Be it known that I, HARRIS T. DUNBAR, a citizen of the United States, residing at Buffalo, in the county of Erie and State of New York, have invented new and useful Improvements in Self-Bailing Scows, of which the following is a specification.

This invention relates to means for bailing a scow or other water craft by utilizing the weight of the load which is deposited upon the scow and removed therefrom as the source of power for effecting the discharge of the water from the hull.

It is the object of this invention to accomplish this purpose by means which are simple in construction, efficient in operation, and require a minimum of attention.

In the accompanying drawings:

Figure 1 is a vertical longitudinal section 20 of a scow embodying my invention, taken on line 1—1, Fig. 2. Figure 2 is a top plan view thereof, partly in section. Figures 3, 4 and 5 are transverse sections taken on the correspondingly-numbered lines in Fig. 1. Figures 6, 7 and 8 are diagrammatic views 25 of the scow showing different positions which the same occupies during the operation of self-bailing the same.

Similar characters of reference indicate 30 corresponding parts throughout the several views.

The hull of the scow is hollow and provided with a flat bottom 10, a flat deck 11 and upright side walls connecting the edges 35 of the bottom and deck and having the main central parts 12 thereof arranged lengthwise while the opposite end portions 13 thereof are inclined toward the longitudinal center of the hull, so that the opposite ends of 40 the latter are tapered or pointed forwardly, but present vertical edges 14 at the extreme ends of the hull.

This hull may be provided with one or 45 more wells extending from the deck to the bottom thereof, two of such wells being shown, for example, in the drawings and each well being designed to form part of a receptacle for carrying the material which is to be transported by the scow. Each of these 50 wells is provided with two longitudinal side walls 15 which are arranged parallel with each other and two transverse walls 16 and 17 which diverge downwardly from the top of the deck of the hull toward the bottom of the 55 same, the transverse wall 16 being preferably curved while the other transverse wall 17

is preferably straight, as shown in Fig. 1. When two wells are employed in the hull the straight inclined transverse walls of both wells preferably are arranged on the inner 60 sides of the wells or away from the ends of the hull and are joined at their upper ends so as to form an apex 18 whereby any material dropped upon the central part of the scow will be divided by this apex and caused 65 to flow downwardly partly into each one of the wells.

In the case of two wells being arranged lengthwise next to each other in the hull the curved transverse walls 16 are arranged next 70 to the ends of the hull.

The lower or outlet end of each well is controlled by a door which is moved into a position across this outlet so as to form with the well a pocket or receptacle which receives the 75 load to be transported and this door is movable out of a position across this outlet, so as to permit the load to be discharged from this pocket when the material has been transported to the place where the same is to be 80 discharged. In the preferred construction of this door the same is made hollow and comprises end heads 190, an upper flat wall 19 and a lower curved wall 20 which connects at its several edges with the corresponding edges of the front wall 19 and heads 190 and forms therewith a buoyant body, the upwardly-swinging movement of which is assisted by the water when the door is free. The bottom 20 of each door is 85 curved about a horizontal axis which is transverse to the bottom, and one end of the same is preferably arranged comparatively close to the straight inclined wall 17 of the well so as to form a practically tight joint 90 therewith, while its opposite end may be spaced apart or fitted comparatively loose relative to the curved transverse wall 16, as 95 shown in Fig. 1.

Various means may be employed for supporting each door on the hull, those shown in the drawings comprising two arms or hangers 21 which project upwardly from opposite longitudinal ends thereof and provided at their upper ends with laterally projecting trunnions 22 which are arranged horizontally or transversely and journaled in suitable bearings 23 on the adjacent parts of the deck of the hull. The curved lower wall 20 of each door is concentric with the 100 axis of the trunnions 22 and the curved transverse wall 16 of the respective well is 105

also preferably concentric with the trunnions, as shown in Fig. 1, which causes the lower wall of the door to always travel fairly close to the straight transverse wall 17 but remain clear of or spaced apart from the curved wall 16.

The upward movement of each door on that side of the well having the curved transverse wall 17 is limited by a stop device 10 while the scow is being loaded and while the load is being transported, but this stop device may be shifted to permit the door to continue its upward movement on that side of the well having the curved wall 16 when it is desired to uncover or open the lower end of the well and permit the load to be discharged therefrom by gravity. In its preferred form, this stop device comprises an outer or rear toggle link 24 which is pivoted 15 on the deck of the hull adjacent to the central part of the curved transverse wall 16 thereof, so that the same is capable of swinging in a vertical plane, and an outer or front toggle link 25 which is pivotally connected with the inner link 24 so as to be capable of swinging in a vertical plane relatively thereto. When the scow is emptied, each of the doors is moved by gravity into a position in which it closes the lower or 20 outlet end of its well in which position the upper wall 19 of the door is horizontal, or substantially so, as shown by full lines in Fig. 1. When loading this scow, the material is dropped into the wells so that the greater part of the same rests upon the horizontal wall 19 of each door and the adjacent straight inclined wall 17 of the respective well, while a comparatively small part of the load is arranged on that part 25 of the lower wall 19 adjacent to the curved wall 16, as shown by dotted lines in Fig. 1, thereby causing the weight of the material in each well to turn each door, so that that end thereof next to the inclined wall 17 would be lowest and that end next to the curved wall 16 will be elevated, the movement in this direction being, however, arrested before the well is uncovered at its lower end by engagement of the elevated 30 end of the door with the front end of the outer toggle link which at this time is shifted so as to project into the path of the door. The two toggle links are held at this time in a position in which they are practically rigid by engagement of the inner toggle link with the adjacent part of the curved transverse wall 16 of the respective well, so that the point of engagement between the door and the outer toggle link and the 35 pivotal connections between the inner toggle link and the hull and outer toggle link are on a dead center and remain rigid under the thrust exerted against the same by the door which tends to move forward at the respective end by the preponderating pressure.

of the load bearing against the opposite end thereof.

When it is desired to dump the material from one of the wells, the attendant disengages the toggle stop device from the respective door and swings the same vertically out of the path thereof and against the deck of the hull. When this is done, the door is immediately turned into an opened position so that the same uncovers the lower or outlet end of the well, this opening movement of the door being automatic and effected by the preponderating weight of the material resting upon the upper floor 19 thereof between the axis of the door and the straight transverse wall 17 of the well, which movement is aided by the buoyancy of the door, due to its hollow construction. As the door rises on that side next to the curved wall 16, the upper wall 19 of the door assumes a gradually increasing inclination while at the same time the material slides down the inclined transverse wall 17, whereby the entire load is discharged from the well through the lower end or outlet thereof. As soon as the material has slid off from the door the same again returns by gravity into its lower position in which it extends across the outlet of the well, and then the operator again shifts the locking device from the top of the deck 30 into a position in which it stands in the path of that edge of the door next to the curved wall 16 ready to arrest the upward movement thereof and keep the door in its closed position, when a load of material is deposited in the well.

In order to permit the load to discharge promptly from the well and the door to clear itself effectively of the material deposited upon the upper wall 19 thereof, the transverse edge 26 of the well at the lower end of the straight wall 17 is arranged farther from a vertical plane extending through the axis of the door than the transverse edge 27 of the well at the lower end of the curved wall 16, as shown in Fig. 1. As soon as that end of the floor next to the straight wall 17 passes beyond the lower edge 26 thereof the material immediately begins to discharge from the well, which discharge is gradually accelerated as the door continues to swing vertically in the same direction. In order to still further facilitate the discharge of the material from the well and avoid any clogging action, that part of the outlet of the well below the transverse edge 26 is undercut, as shown at 28, whereby any material after passing below the edge 26 will be immediately fully liberated and permitted to drop out of the well without any restriction.

In order to increase the loading capacity of the scow and to protect the bearings on the deck which support the pivots of the doors, two coamings 29 are arranged lengthwise upon the deck along opposite sides of

the wells, so as to enclose the inner parts of the bearings of the doors, thereby preventing the bucket of the dredging apparatus, as the same swings over the scow, from injuring these bearings. As shown in the drawings, the several walls or parts of the hull forming the shell of the same and the main parts of the doors are constructed of sheet metal, but it is to be understood that these parts may 10 be constructed of other materials, if desired.

The means for utilizing the weight of the material which is loaded into the scow to furnish the power for obtaining practically a self-bailing effect are constructed as follows:

30, 31 represent two upright bulkheads which extend transversely of the hollow interior of the hull at a distance from the opposite ends thereof, so as to divide this interior of the hull generally into two end chamber sections and an intermediate chamber section. The end chamber section 32 may extend the full height of the scow and be divided by a central vertical longitudinal bulkhead 35 which is tight and two side longitudinal partitions 36 which extend downwardly from the deck but terminate short of the bottom of the hull, so as to leave a passage 37 thereunder, as shown in Figs. 1 and 5. The other end chamber section is divided horizontally by a partition 38 into a lower primary bilge water chamber 39 and an upper trap chamber 40, and these chambers are also divided vertically by a central longitudinal bulkhead 41 which is tight, and two side longitudinal partitions 42 which extend downwardly from the deck and terminate short of the bottom of the hull, so as to form passages thereunder, as 40 shown at 43 in Figs. 1 and 3.

The intermediate chamber section consists of two longitudinal intermediate chambers 33 arranged lengthwise on opposite sides of the wells, and a transverse intermediate chamber 44 which communicates at its opposite ends with said longitudinal chambers. This transverse intermediate chamber is divided centrally by a tight upright bulkhead 45 and is separated at its ends from the longitudinal 50 chambers by upright longitudinal partitions 46, which extend downwardly from the deck and terminate short of the bottom of the hull, so as to form passages 47 thereunder, as shown in Figs. 1 and 4. Each of the upright 55 side partitions is preferably provided with a manhole 48 to afford access to the interior of the hull for inspection and repairing.

49 represents two emergency valves which control ports or passages whereby communication is established between the primary chamber 39 and the adjacent ends of the longitudinal chambers 33 of the intermediate section, and 50 represents similar valves which control ports or passages whereby 65 communication is established between the

opposite ends of these longitudinal chambers 33 and the opposite end chamber 32 of the hull. 51 represents two transfer ducts or conduits arranged lengthwise in the longitudinal chambers, respectively, and each 70 communicating at its lower end with the end chamber 32 adjacent to the bottom of the hull while the elevated end of each of these transfer conduits communicates with the trap chamber 40 at a distance above the bottom of the latter, as shown in Figs. 1, 3 and 5. Each of the transfer conduits is provided with an emergency valve 52.

53 represents two drain pipes arranged on opposite sides of the hull and each containing a hand operated valve 54 and having its upper end opening into the trap chamber at the bottom thereof while its lower end extends to the exterior of the hull at a point below the trap chamber, this being 85 preferably accomplished by extending these drain pipes through the bottom of the hull, as shown in Figs. 1 and 3.

The valves 49, 50, 52 and 54 have their stems extending upwardly above the deck 90 where they are accessible to the attendant but preferably have their handles arranged under the coamings where the same are out of the way and not liable to be damaged while operating the scow.

Assuming that the valves 49, 50 and 52 are open and the valves 54 closed, and the scow is empty and setting high in the water, as shown in Fig. 1, the operation of bailing the hull while loading and unloading the 100 scow is as follows:

First, the well next to the end chamber 32 is loaded with material which rests principally on the wall 17 and the adjacent part of the door of the respective well, 105 whereby this door is tilted somewhat and the corresponding end of the hull is sunk deeper into the water, as shown in Fig. 6. This causes any water which may have leaked into the hull to gather in the end 110 chamber 32 inasmuch as any water at this time in the primary chamber 39 will flow from the same through the valves 49 into the intermediate chamber section and from the latter through the valves 50 into the 115 gathering chamber 32. The valves 50 are now closed and the other well is filled with material corresponding to the first-mentioned well, whereby the hull is caused to settle uniformly in the water or substantially so, throughout its length, as shown in Fig. 7. The well next to the gathering chamber 32 is the first to be emptied, which causes the corresponding end of the hull 120 when relieved of its load, to rise while the opposite end of the hull which is still loaded remains deeper in the water, as shown in Fig. 8. When this occurs, any water in the gathering chamber 32 flows from the same through the transfer conduits 51 into the 130

trap chamber 40. If now the load is discharged from the well next to the trap chamber, that end of the hull also rises so that the entire hull sets high in the water and the water in the trap chamber cannot return to the gathering chamber, owing to the discharge ends of the transfer conduits 51 being arranged at a distance above the bottom of the trap chamber. When the hull 10 is thus relieved of its burden and sets high in the water the level of the latter is below the bottom of the trap chamber, as shown in Fig. 1. Upon now opening the drain valves 54, any water in the trap chamber 15 will flow from the same through the drain pipes to the exterior of the hull after which these valves are again closed and the bailing operation for the time being is completed and may be repeated in the manner described as often as necessary or desired. It 20 is to be noted that by this means the hull of the scow, excepting for the manipulation of the valves, is practically self bailing, and that the actual work of ejecting the water 25 from the hull is done by power which is derived from the weight of the material which is loaded into the hull, thereby effecting a considerable economy in the operation of a scow inasmuch as the cost of separate pumping 30 ing for this purpose is saved.

In the event that any of the compartments become punctured, the emergency valves 49 and 52 are closed to prevent all of the compartments from being flooded and sinking 35 the scow.

I claim as my invention:

1. A scow comprising a hollow hull provided at one end with a trap which is elevated above the bottom of the hull while 40 its other end is provided with a lower chamber extending down to the bottom of the hull, and a valved conduit leading from said lower chamber to said elevated trap.

2. A scow comprising a hollow hull provided at one end with a trap which is elevated above the bottom of the hull while its other end is provided with a lower chamber extending down to the bottom of the hull, a 45 valved conduit leading from said lower chamber to said elevated trap, and a valved drain conduit leading from said trap to the exterior of said hull and to a point below said trap.

3. A scow comprising a hollow hull provided adjacent to one end with a transverse bulkhead and a horizontal partition arranged above that part of the bottom between 55 said bulkhead and the adjacent end of the hull and forming a lower bilge chamber and an upper trap chamber, a transverse bulkhead arranged at the other end of the hull and forming with the latter a gathering chamber extending to the bottom of the hull and communicating with said lower 60 bilge chamber by a valved conduit, and

a transfer conduit extending from the gathering chamber adjacent to the bottom thereof to the trap chamber above the partition forming the bottom thereof.

4. A scow comprising a hollow hull provided adjacent to one end with a transverse bulkhead and a horizontal partition arranged above that part of the bottom between 70 said bulkhead and the adjacent end of the hull and forming a lower bilge chamber and an upper trap chamber, a transverse bulkhead arranged at the other end of the hull and forming with the latter a gathering chamber extending to the bottom of the hull and communicating with said lower 75 bilge chamber by a valved conduit, a transfer conduit extending from the gathering chamber adjacent to the bottom thereof to the trap chamber above the partition forming the bottom thereof, and a valved drain pipe leading from the bottom of said trap chamber to the exterior of said hull below the trap chamber.

5. A scow comprising a hollow hull provided adjacent to one end with a transverse 90 bulkhead and a horizontal partition arranged above that part of the bottom between said bulkhead and the adjacent end of the hull and forming a lower bilge chamber and an upper trap chamber, a transverse bulkhead arranged at the other end of the hull and forming with the latter a gathering chamber extending to the bottom of the hull and communicating with said lower 95 bilge chamber by a valved conduit, a transfer conduit extending from the gathering chamber adjacent to the bottom thereof to the trap chamber above the partition forming the bottom thereof, and a valved drain pipe leading from the bottom of said trap chamber to the exterior of said hull below the trap chamber.

6. A scow comprising a hollow hull provided adjacent to one end with a transverse 100 bulkhead and a horizontal partition arranged above that part of the bottom between said bulkhead and the adjacent end of the hull and forming a lower bilge chamber and an upper trap chamber, a transverse bulkhead arranged at the other end of the hull and forming with the latter a gathering chamber extending to the bottom of the hull and communicating with said lower 105 bilge chamber by a valved conduit, a transfer conduit extending from the gathering chamber adjacent to the bottom thereof to the trap chamber above the partition forming the bottom thereof, and a valve in said transfer conduit.

7. A scow comprising a hollow hull provided adjacent to one end with a transverse 110 bulkhead and a horizontal partition arranged above that part of the bottom between said bulkhead and the adjacent end of the hull and forming a lower bilge chamber and an upper trap chamber, a transverse bulkhead arranged at the other end of the hull and forming with the latter a gathering chamber extending to the bottom of the hull and communicating with said lower 115 bilge chamber by a valved conduit, a transfer conduit extending from the gathering chamber adjacent to the bottom thereof to the trap chamber above the partition forming the bottom thereof, and a valved drain pipe leading from the bottom of said trap chamber to the exterior of said hull below the trap chamber, and a valve in the line of communication between said bilge chamber and the gathering chamber.

8. A scow comprising a hollow hull pro-

- vided adjacent to one end with a transverse bulkhead and a horizontal partition arranged above the bottom of the hull between said bulkhead and the adjacent end of the 5 hull forming a primary bilge chamber and a trap chamber above the primary chamber, a transverse bulkhead arranged at the other end of the hull and forming with the respective end of the hull a bilge gathering 10 chamber, that part of the hollow hull between said transverse bulkheads forming an intermediate bilge chamber, a valve for controlling communication between said intermediate bilge chamber and said gathering 15 chamber, a transfer conduit extending upwardly from said gathering chamber to said trap chamber above the bottom of the latter, and a valved drain pipe extending from 20 said trap chamber to the exterior of the hull and to a point below said trap chamber.
8. A scow comprising a hollow hull provided adjacent to one end with a transverse bulkhead and a horizontal partition arranged above the bottom of the hull between 25 said bulkhead and the adjacent end of the hull forming a primary bilge chamber and a trap chamber above the primary chamber, a transverse bulkhead arranged at the other end of the hull and forming 30 with the respective end of the hull a bilge gathering chamber, that part of the hollow hull between said transverse bulkheads forming an intermediate bilge chamber, a valve for controlling communication between 35 said intermediate bilge chamber and said gathering chamber, a transfer conduit extending upwardly from said gathering chamber to said trap chamber above the bottom of the latter, a valved drain pipe extending from 40 said trap chamber to the exterior of the hull and to a point below said trap chamber, and valves controlling communication between said primary bilge
- chamber and said intermediate chamber and between said gathering chamber and said trap chamber.
9. A scow comprising a hollow hull having a door controlled well extending from the top to the bottom thereof, intermediate chambers arranged lengthwise on opposite sides of said well, a lower primary bilge chamber arranged at one end of the hull and communicating with both of said intermediate chambers and a trap chamber arranged above the primary bilge chamber, a gathering chamber arranged at the opposite end of the hull and communicating by valved passages with the respective ends of said intermediate chambers, and inclined transfer conduits arranged in said intermediate chambers and extending from the gathering chamber adjacent to the bottom thereof to the trap chamber above the bottom of the latter.
10. A scow comprising a hollow hull having a door controlled well extending from the top to the bottom thereof, intermediate chambers arranged lengthwise on opposite sides of said well, a lower primary bilge chamber arranged at one end of the hull and communicating with both of said intermediate chambers and a trap chamber arranged above the primary bilge chamber, a gathering chamber arranged at the opposite end of the hull and communicating by valved 65 passages with the respective ends of said intermediate chambers, and inclined transfer conduits arranged in said intermediate chambers and extending from the gathering chamber adjacent to the bottom thereof to the trap chamber above the bottom of the latter, said end chambers being divided 70 lengthwise by upright bulkheads arranged on the median line of the hull.

HARRIS T. DUNBAR.
